WEB-REGISTERING DEVICE

Franklin H. Wells, Hackensack, N. J., and John J. Root, Hastings on Hudson, N. Y., assignors to American Machine & Foundry Company, a corporation of New Jersey

Application April 25, 1940, Serial No. 331,582

6 Claims. (Cl. 271—2.6)

This invention relates to web-registering devices, and an object of the invention is to control wrapping or packaging machines by controlling the feeding of the web of wrapping material, which is provided with recurrent printed indicia or patterns, to stop the web in predetermined position for the wrapper-severing operation. To this end there may be employed the "capacity effect" of electrically conductive spots spaced along the web to produce a current in a high frequency electrical circuit and this current, after proper amplification, is used to control the feeding of the web to bring the recurring indicia or patterns in registry with the cutter and thereby to control the feeding and the cutting of the web relative to the printing thereon.

The electric capacitance or "permittance" between two plates in a high-frequency circuit depends upon the dielectric or insulating properties of the material or materials present in the space between the plates. Thus, if a web of insulating material, such as Cellophane, paper or waxed paper, having recurrent index spots M of high dielectric constant—such as bronze or other metallic particles dispersed in a non-conductive medium or of comparatively high conductivity, such as India ink, is moved through such a space, the capacitance of the circuit changes markedly every time one of the spots passes by. The resulting current impulse, amplified by well known means, may be made to energize an electro-magnet controlling a clutch and thus to stop the feed rollers which advance the wrapping web.

In the accompanying drawings which form a part of this specification and in which like characters of reference indicate the same or like parts:

Figs. 1, 2 and 3 show various methods of arranging the plates A and B for registering index spots M on the web W;

Fig. 4 is a wiring diagram of a suitable circuit for registering the recurring index spots on the web;

Fig. 5 illustrates a modified form of the relative arrangement of the plates and the traveling web;

Fig. 6 is a diagram of a different circuit for registering the recurring spots or marks on the web.

The plates, A, B, may be arranged in opposition as in Fig. 1, in which case a web of material having electrically conductive spots or areas having a dielectric capacity different from the web may be registered; or they may be arranged in align-

ment as in Fig. 2; or upon the periphery of a drum D, Fig. 3. The distances d between the plates in Figs. 2 and 3 are made less than the length or width of the marks M, so that when the mark M bridges plates A and B it forms two condensers Ca, and Cb, one with each plate, which condensers are connected in series by the mark itself. Thus this device is made much more sensitive.

In Fig. 3, the drum D is made of insulating material and with the plates A and B is enclosed within a cylinder O formed of "Bakelite" or other suitable material revolving on the shaft of drum D. The web W rests on cylinder O and guide roller F' as the same is drawn thereover by the feed roller F which is driven by a chain J through a magnetic clutch K. The driving member of the latter is slidably mounted on the shaft of roller F and controlled by an electro-magnet E which is energized to disengage the driving member from the driven member of the clutch, by amplified current impulses due to the capacity effect of the conducting marks M when passing across the plates A, B when the same are connected in a high frequency oscillating circuit. Every time a mark M reaches a certain critical position relative to the plates A, B, the amplified current impulse causes the electromagnet E to disengage the clutch K and thereby to stop the feed of the web W.

In the circuit shown in Fig. 4, A and B are the detector plates, C1—C17 are condensers, E is the electro-magnet for disengaging the magnetic clutch K, F and F' are rollers for respectively feeding and guiding the web W, G are ground connections, H is a spring for holding the clutch in engaged position, J is a chain driving the clutch which through bevel gears N drives the feed roller F, L indicates the power lines, and M is one of the recurring electrically conductive marks on the web W. P1 and S2 are the primaries of transformers T¹ and T² whose secondaries are indicated at S1 and P2; P3 is the primary of a power transformer T³ connected to the lines L and having secondaries S3', S3'' and S3'''; Q1, Q2 are grounded cables leading to the plates; R1—R10 are resistors; S_{w1} is a line switch; S_{w2} is a reset switch; T¹ may be a 175 kc. intermediate frequency transformer; T² may be a 175 kc. oscillating transformer; T⁴ is a power choke coil; V¹ is a 6S.J.7 detector tube; V² is a 2051 grid glow tube; V³ is a 5T4 power rectifier tube; V⁴ is a 6J5 oscillatory tube; and V⁵ is a 6J5 C-bias rectifier tube; and VC₁, VC₂ and VC₃ are variable condensers.

The condensers and resistors used may be of the following magnitudes, by way of example:

C1	microfarad	.0001
C2	do	.0001
C3	do	.0005
C4	do	.00025
C5	do	.01
C6	do	.0005
C7	do	.01
C8	do	.05
C9	do	.01
C10	do	.05
C11	do	.05
C12	do	.03
C13	do	.1
C14	do	.01
C15	do	.01
C16	do	8
C17	do	8
R1	ohms	25,000
R2	do	150,000
R3	do	10,000
R4	do	100,000
R5	do	2,000,000
R6	do	25,000
R7	do	50,000
R8	do	250,000
R9	do	1,000,000
R10	do	1,000,000

In order to understand the operation of the capacity-effect of the registering device, five principal circuit functions must be kept in mind:

(1) An oscillator may be used to generate a high-frequency A. C. potential. The oscillating circuit in the present device consists of the transformer T2 and vacuum tube V4.

(2) A detector tube detects the A. C. potential picked up through detector plates A, B and ink mark M, the detector circuit in this case being formed by vacuum tube V1 and transformer T1.

(3) An amplifier circuit using a grid glow tube amplifies the impulse from the detector circuit. This tube is designated at V2 and is connected to the electromagnet E to actuate the clutch K which operates and stops the web feed.

(4) Vacuum tubes V1 and V2 require an opposing negative C-bias for their operation, this C-bias being furnished by tube V5. Part of the voltage generated by tube V4 is rectified by tube V5 and applied to the respective circuits.

(5) Transformer T3, choke coil T4 and rectifier tube V3 furnish the direct current necessary for the operation of the complete unit.

Tracing the complete circuit shown in Fig. 4, the operation of the various units is as follows:

The oscillating circuit transformer T2 and tube V4 generate a potential having an A. C. frequency with a range of approximately 10-175 kilocycles. This A. C. potential is applied in two ways: It is fed through condenser C3 to resistor R8. Rectifier tube V5 rectifies the potential across R8 and applies a D. C. voltage across adjustable potentiometers R9 and R10. The tap on potentiometer R9 applies a negative C-bias to tube V2, properly filtered by condensers C11, C10 and C1. The tap on potentiometer R10 applies a negative D. C. voltage to the grid of tube V1, properly filtered by condensers C10, C11 and C9.

The oscillator voltage is also fed through condenser C2, through shielded cable Q1 to plate A, so that there will be an increased capacitative coupling through mark M to cause a current impulse in plate B, and on through cable Q2 and condenser C1 to the primary P1 of the interme-

diate tuned transformer T1. Condensers C1 and C2 are in the circuit to diminish the parallel capacity effects of cables Q1 and Q2. This same current impulse induces a current in the secondary S1 of transformer T1 and is applied to the grid of tube V1, and it will be understood that the variable condensers VC1, VC2 and VC3, are adjusted to create resonant conditions of the oscillating, detector and amplifying circuits. Tube V1 has a resistor R2 in its cathode circuit and a resistor R4 in its plate circuit. Tube V1 in normal operation is biased almost to current cut-off by potentiometer R10, and no voltage is developed across resistors R2 and R4. Now, when the current impulse conducted through the mark M is imposed on the grid of tube V1, only the positive half of the cycle of induced current impulse causes current to flow in the cathode and plate circuits of tube V1, thereby causing one D. C. voltage to develop across resistor R2, filtered by condenser C5, and one D. C. and A. C. potential to develop across resistor R4 which is not filtered.

These two voltage components trip the lock-in circuit in tube V2 in the following manner: Tube V1 being a combined D. C. and pulsating current amplifier, the positive voltage component across resistor R2 is fed in series through potentiometer R9, which normally biases tube V2 to cut-off, and is applied through grid resistor R5 to the grid of tube V2, and at the same time the pulsating current potential across R4 is applied through condenser C6 across resistor R5 and to the grid of tube V2. Now, tube V2 is a gaseous tube, and gaseous tubes have a lock-in characteristic when operated on D. C. When a small potential is applied to the grid of tube V2, the gas ionizes and causes this tube to pass current, thereby energizing the electro-magnet E of the clutch K. It will be understood that instead of the lock-in circuit a relay may be used, connected to tube V1 for energization of the electromagnet K.

Tube V2 is not capable of returning to normal operating condition until switch SW2 is opened and closed again. For this purpose a rotary cam 45 may have a suitable cam track engaging a cam follower Y on the switch SW2 and operating in each cycle of operations to momentarily open switch SW2 and then close the same whereby the electromagnet E is deenergized and the circuit 50 reset for operation on the next spot on the web. Condenser C12 charges up in an opposite polarity when tube V2 fires, thereby assisting deionization of tube V2 when the switch SW2 is used to reset the operation condition of the circuit.

Resistor R1 in conjunction with condenser C16 acts as a line voltage surge stabilizer, wherefore fast line voltage surges will not trip the circuit. Condensers C14 and C15 prevent any A. C. voltage from leaking into the line from the oscillator.

In the arrangement of the plates shown in Fig. 5, the plates A, B are placed in alignment with each other and a grounded plate C is disposed in the gap between plates A and B to reduce their coupling to a minimum and thereby gain greater sensitivity. When a mark M bridges the gap between the plates A and B, a current impulse is set up which is amplified and applied to the clutch disengaging magnet, as described above.

Another circuit is shown in Fig. 6. Here, the web W is drawn between the primary P and the secondary S of a transformer T connected to an oscillator tube V. The secondary S has 75 in its circuit a condenser C and a resistor R. The

primary P and secondary S are adjusted to be at or near a critical condition by adjusting the gap therebetween or otherwise so that the spot or mark M affects the coupling between primary P and secondary S and sets up an impulse, which after amplification, energizes a relay Re which actuates electro-magnet E to disengage the magnetic clutch (not shown) through which is driven the feed roller F engaging the web W. The currents for the relay Re and for the filament of tube V are supplied by batteries B1 and B2. The spots M may be formed with conductive ink or ink containing magnetic material, such as iron powder. Moreover spots or areas having dielectric properties different from the remainder of the web may be used to vary the coupling between primary P and secondary S sufficiently to energize the electromagnet E.

While the invention has been exemplified as stopping the feeding of the web in a predetermined registered position it will be understood that it may serve to control the feeding to obtain the desired registration, and is not limited to web-registering devices.

What is claimed is:

1. A web registering device comprising means for feeding a web of material having recurrent spots of material having a dielectric capacity different from the web, condenser plates spaced from and extending into the proximity of said web, a high frequency electric circuit connected to said plates and adapted to be affected by capacitive coupling between said plates and said spots successively, a device controlled by said circuit for terminating the feeding action of said means when said plates are capacitatively coupled by one of said spots, to stop successive spots in predetermined registered position, and means for incapacitating said device and reinstating the operation of the web feeding means to advance the next spot on the web into position to capacitatively couple said condenser plates.

2. In a web-registering device, the combination with means for feeding a web of material having recurrent spots having a dielectric capacity different from the web of material, of detector plates spaced from and extending into the proximity of said web, a high frequency electric circuit connected to said plates and adapted to be affected by capacitive coupling through each of said spots successively, and an electromagnetic device controlled by said circuit for interrupting the feeding action of said means to stop successive spots on said web in predetermined registered position, a drum carrying said plates, which are disposed on said drum, and a rotating cylinder formed of insulating material and enclosing said drum.

3. In a web-registering device, the combination with means for feeding a web of material having recurrent spots of material having a dielectric capacity different from the web, of condenser plates spaced from and extending into the proximity of said web, an electric circuit connected to said plates and adapted to be affected by capacitive coupling through each of said spots successively, and an electromagnetic device controlled by said circuit for interrupting the feeding action of said means to stop successive spots on said web in predetermined registered position, said circuit including an oscillatory circuit coupled to one of said plates a detector circuit coupled to the other of said plates, and a lock-in circuit connected to said detector circuit, and said device including an electromag-

net connected to said lock-in circuit and adapted to be energized by said lock-in circuit and stop said feeding means when a spot on said web establishes a capacitative coupling of said plates, and a switch for breaking the lock-in circuit and deenergizing said electromagnet to rehabilitate said feeding means.

4. A wet registering device comprising means for feeding a web of material having recurrent printed spots containing electrically conductive material, flat condenser plates spaced from and extending into the proximity of said web, a high frequency alternating current electric circuit connected to one of said plates, a detector circuit connected to the other of said plates and adapted to detect an electrical impulse created by capacitative coupling of said plates established by each of said spots successively, and a device controlled by said detector circuit for interrupting the feeding action of said means to stop successive spots on said web in predetermined registered position, said plates being disposed on the same side of the web and out of contact with said spots and web and spaced from each other whereby the capacitative coupling of said plates with each of the successive spots will form a pair of condensers connected in series which serve to affect the detector circuit sufficiently during said capacitative coupling to operate said device and thereby stop the feeding of said web by said means.

5. In a web-registering device, the combination with means for feeding a web of material having recurrent printed spots containing electrically conductive material, of a pair of condenser plates spaced from and extending into the proximity of said web, a high frequency alternating current electric circuit adapted to be affected by capacitive coupling through each of said spots successively, and a device responsive to variations in the current flow in said circuit due to capacitative coupling of one of said spots with said plates for interrupting the feeding action of said means to stop successive spots on said web in predetermined registered position, each of said condenser plates being disposed out of contact with said web and spaced from and aligned with each other, each of said pair of condenser plates being connected to said circuit, and a grounded third plate disposed between said pair of plates and unconnected to said circuit.

6. The combination with means for feeding material having electrically conductive indicia thereon, of a pair of condenser electrodes spaced from each other and extending into the proximity of and out of contact with the material advanced by said means, an oscillator circuit connected to one of said condenser electrodes and adapted to impress high frequency alternating current thereon, a detector circuit connected to the other of said electrodes, and electrical control device connected to said detector circuit and adapted to be operated when an increased coupling of said electrodes is produced by the proximity of electrically conductive indicia on said material, said electrodes being disposed on the same side of said material, and a grounded member interposed between said electrodes and unconnected to said oscillator and detector circuits, to minimize the coupling of said electrodes and thereby increase their sensitivity.
